THE COLUMBIA PLANOGRAPH CO., WASHINGTON, D. C.

UNITED STATES PATENT OFFICE.

JOSEPH ROBERT DOOLEY, OF MOBILE, ALABAMA.

RAILWAY-TIE.

1,317,560.

Specification of Letters Patent. Patented Sept. 30, 1919.

Application filed February 13, 1919. Serial No. 276,744.

To all whom it may concern:

Be it known that I, JOSEPH R. DOOLEY, a citizen of the United States, and a resident of Mobile, in the county of Mobile and State 5 of Alabama, have invented a new and Improved Railway-Tie, of which the following is a full, clear, and exact description.

This invention relates to railway ties, and has for an object to provide an improved 10 tie and improved means for securing the rail thereto. The nature and objects of the invention will more fully appear upon inspection of the following specification and the accompanying drawings forming a part 15 thereof.

In the drawings, Figure 1 is a plan view of a tie embodying the invention and showing the rails secured thereto;

Fig. 2 is a side view and partial section 20 taken on the line 2—2 looking in the direction of the arrows;

Fig. 3 is a transverse sectional view taken on the line 3—3, Fig. 1, looking in the direction of the arrows;

Fig. 4 is a perspective view of one of the 25 filler blocks or cushioning members;

Fig. 5 is a perspective view of a four-hole wear plate;

Fig. 6 is a plan view showing a modified 30 construction;

Fig. 7 is a transverse sectional view taken on the line 7—7, Fig. 6;

Fig. 8 is a partial, longitudinal, central 35 sectional view of the construction shown in Fig. 6;

Fig. 9 is a plan view of a wear plate and side brace applied to a tie, the rail being shown in section;

Fig. 10 is a sectional view taken on the 40 line 10—10, Fig. 9;

Fig. 11 is a transverse sectional view on the line 11—11, Fig. 9; and

Fig. 12 is a perspective view of the spike or rail-securing hook.

45 In the construction shown in Fig. 1 for the purpose of illustrating the invention, the tie comprises two sections 1, 2 secured together at the center by means of a two-part link 3. Each section is provided with 50 a recess 4 which, preferably, is wider at the top than at the bottom to provide a slight taper, but shorter in length at the top than at the bottom longitudinally of the tie in order that the recess may be undercut, and 55 preferably at both ends. Within this recess are positioned three cushioning blocks 5, 6,

7, preferably of wood. It is sufficient to provide means for locking the central cushioning member in place, and, accordingly, the two side cushioning members are 60 shorter and of a different shape in that the two ends thereof are parallel. The recess is shaped to receive the three blocks as a whole and, accordingly, is irregular in shape at its inner end, a shoulder 9 being formed 65 to fit against the inner end of each side cushioning member. The central cushioning member 5 is shorter than the under-cut recess 4 to permit insertion and removal thereof; and in order to secure the same in 70 place, a wedge 10 is provided at one end. Preferably a locking member for holding the wedge in place is provided. As shown, a plate 11 having a lower inturned end 12 fits against and under the end of the central 75 cushioning block at the inner end of the block. After the wedge 10 is driven into place to secure the cushioning member firmly in the recess, the upper end of the plate is bent over the top of the wedge to prevent 80 loosening thereof. The locking plate of tie section 2 is shown as straight, while that of section 1 is shown in finished bent condition.

Metal wear plates 14, 15 are mounted upon the cushioning members to receive the rails. 85 The wear plates may be provided with four square holes to receive rail-securing hooks, or may be provided with a less number of holes, depending upon the stress to which the rails are to be subjected in use. In the 90 construction shown in Fig. 1, which is designed for use upon a curve, the wear plate 14 on the left-hand side is provided with four holes for four rail-securing hooks, to secure the outer rail; whereas the wear plate 15 for the inner rail of the curve is provided with only two holes for rail-securing hooks. The reason for this is, of course, that the greater strain comes upon the outer rail. 95

Each wear plate is provided at its inner 100 end with a flange 16 which fits a corresponding recess or shoulder of its cushioning block. The central cushioning block is formed, preferably, with straight sides and is, thus, rectangular in cross section, as 105 shown in Fig. 3. Four channels or grooves 18, 18 are formed in the opposite sides of the central cushioning block 5 to receive the shanks of the rail-securing hooks 19, 19. The hooks engage beneath the central 110 cushioning block and over the flanges of the rail, thereby securing the rail firmly in

place. These hooks may be made in the form shown, with hooks at both ends of the shanks, or they may be formed with hooks at the lower ends of the shanks for engagement beneath the cushioning members, and may be left straight to be bent over the rail at the time of laying the rails. The latter method is desirable in some instances for convenience in assembling. The recess 4 in the tie is provided at its base with transverse grooves 20, 20 to receive the lower ends of the hooks 19, 19, and is also preferably provided with a recess at the inner end to receive the end of the wedge-securing plate 11.

The connecting link 3 between the two tie sections is formed of two similar parts 21, 21 each having an eye 22 to receive the end of the other part, and nuts upon the threaded ends securing the parts together.

In the construction shown in Fig. 6, which is designed for lighter service, the two concrete tie sections 25, 26 are secured together by a simpler form of link 27, consisting of a rod bent at right angles at its ends to engage in holes 28, 29 in the tie sections. One cushioning block 30 only is used, and this cushioning block may be made tapered in cross section (see block 31 in Fig. 7) or rectangular in cross section (see block 32 on Fig. 11). The wedge securing plate is also omitted in this construction.

In Fig. 9 is shown a wear plate 33 provided with a rail-engaging brace 34 for use upon the outer rail at a curve of the track to brace the rail against side thrusts. The said plate is formed from a sheet-metal blank bent at its outer end to form a brace 34 projecting against the web of the rail. At each side of this brace are provided webs 35, 35 which are formed by bending downwardly the sides of the blank, and at the inner end each web is formed with an outwardly-flanged 36 designed to fit against the rail. At the inner end of the plate, instead of employing merely the hooks, such as previously described, a securing plate 37 may be employed, such plate fitting flat against the wear plate and being provided with an offset flange projecting over the rail flange. This plate is secured in place by hooks, as previously described, but preferably the hooks are bent laterally instead of being swaged over the rail flange as in the constructions previously described. (See Figs. 9, 10 and 11). It is to be noted that the tie is formed in two sections with means for connecting the meeting ends thereof. Such a tie greatly facilitates repairs, for if one rail only needs resetting, or if one end of the tie becomes disarranged or worn out, it is only necessary to release the connecting de-

vice and remove one section of the tie. Under normal conditions the connecting device forms practically a single tie of the two sections.

I claim:

1. A railway tie and rail-securing device including two concrete tie sections, each section having an under-cut recess; means to maintain said sections in predetermined relation to each other, consisting of a link formed of two duplicate parts, each presenting a side bar and a cross bar, the cross bar of each part fitting into an eye in the free end of the side bar of the other part; cushioning blocks in said recesses; means for securing the rails to the cushioning blocks; and means for securing said cushioning blocks in said recesses.

2. In a device of the character described, in combination, a concrete tie section having an under-cut recess; a cushioning block secured in said recess having channeled sides; and rail-securing devices fitting in the channels of the sides of the cushioning blocks and having hooks to extend under the blocks and over the rail flanges.

3. In a device of the character described, in combination, a concrete tie section having an under-cut recess; three parallel cushioning blocks in said recess; a wear plate resting on said cushioning blocks; and rail-securing devices fitting in vertical channels between said blocks and extending through the wear plate and having hooks to engage beneath one of the cushioning blocks and over the rail flanges.

4. In a device of the character described, in combination, a concrete tie section having an under-cut recess; three parallel cushioning blocks in said recess; a wear plate resting on said cushioning blocks and having a downwardly-extending flange engaging one of said cushioning blocks to resist lateral movement of the plate; rail-securing devices to secure rails to said blocks; a wedge to secure at least one of the cushioning members in the recess; and a locking member extending under a cushioning block and over the wedge.

5. In a device of the character described, in combination, a concrete tie section having an under-cut recess; three parallel cushioning blocks in said recess; a wear plate resting on said cushioning blocks, said wear plate having one end bent over to form a brace to engage the rail web and having side portions forming reinforcing webs; and rail-securing devices fitting in vertical channels between said blocks to secure a rail to one of the cushioning blocks.

JOSEPH ROBERT DOOLEY.
